Primary Examiner—Mitchell Siegel

(**) Term: **14 Years**

(57) **CLAIM**

(21) Appl. No.: **29/124,771**

The ornamental design for an golf club putter, as shown and
described.

(22) Filed: **Jun. 12, 2000**

DESCRIPTION

(51) LOC (7) Cl. **21-02**
(52) U.S. Cl. **D21/743**
(58) Field of Search D21/736-746;
473/251-256, 324, 327, 328, 340, 341

FIG. 1 is a right side elevational view of the golf club putter
showing my new design;

FIG. 2 is a left side elevational view thereof;

FIG. 3 is a front elevational view thereof;

FIG. 4 is a rear elevational thereof;

FIG. 5 is a top elevational plan view thereof; and,

FIG. 6 is a bottom elevational plan view thereof.

The broken line showing of a fragmented shaft on FIGS. 3
and 4 is for illustrative purposes only and forms no part of
the claimed design.
